A. E. LINDENSCHMIDT

RECORD COUPON ENVELOPE

Filed Oct. 2, 1922

INVENTOR:

August E. Lindenschmidt

BY

Glen L. Allard
ATTORNEY'S.

UNITED STATES PATENT OFFICE.

AUGUST E. LINDENSCHMIDT, OF FORT THOMAS, KENTUCKY.

RECORD COUPON ENVELOPE.

Application filed October 2, 1922. Serial No. 591,734.

To all whom it may concern:

Be it known that I, AUGUST E. LINDENSCHMIDT, a citizen of the United States, and a resident of Fort Thomas, in the county of 5 Campbell and State of Kentucky, have invented certain new and useful Improvements in Record Coupon Envelopes, of which the following is a full, clear, and exact description, reference being had to the 10 accompanying drawings, forming part of this specification.

The object of my invention is to provide a construction of duplicate envelopes especially designed for the holding of interest 15 coupons and the like, which it is desired to deposit in bank or other collection agency for collection, and which shall permit the collecting agency to transmit the coupons as deposited in one envelope while retaining 20 the other envelope, upon which data is made which it is not desired to transmit to the place of payment of the coupons.

It is customary for banks, trust companies and other collecting agencies to provide 25 coupon envelopes for the use of their depositors when cashing or depositing any Government, municipal or other coupons, and these envelopes usually bear the name of the depositary, provide space for description 30 of the coupons, number, amount, date when due, where payable and so forth, also a line for the name of the depositor. The envelopes with coupons enclosed are forwarded to the place of payment by the bank.

35 A great many of the larger banks and trust companies, in order to give better service to their customers, many of whom object to having their names sent with coupons, erase the depositor's name (if given) and 40 for the purpose of tracing the coupons (in the event they are returned or lost) keep a coupon record book in which the name of the depositor and other details are entered; these entries are numbered and the number 45 given to the entry is placed on the envelope containing the coupons.

It is to obviate the necessity for keeping 50 this coupon record book and to permit the forwarding of the coupons in the envelope in which they are placed by the depositor, without any indication of the name of the depositor, while the bank retains a duplicate envelope containing the same record and in addition the name of the depositor 55 and any other data which it is not desirable to transmit, that my invention is directed,

and it consists essentially in the employment of two envelopes, the one fitting snugly within the other, both envelopes being ruled and spaced to receive the essential data desired for transmission, with the inside of the outer envelope carbonized in a zone necessary to make a carbon transfer of this data, while the outer envelope also is additionally ruled and spaced to receive other data, but these portions of the outer envelope are not carbonized, so that no transfer is made of the additional information upon the inner envelope which contains the coupons.

In the drawings,

Figure 1 is a plan of the outside envelope taken from the front side.

Figure 2 is a similar view of the inside envelope.

Figure 3 is a plan of the outer envelope viewed from the rear with a portion of the front torn away to indicate the zone of carbonization.

For the depositor two envelopes of ordinary construction are provided 1 and 2; the outer envelope is of a size to snugly receive the inner envelope.

The inner envelope is an ordinary envelope with the usual side flap for mailing purposes. The outer envelope, however, which is intended for filing, is preferably open at the end, and the back is also made of paper or cardboard sufficiently stiff to make it adequately rigid for filing purposes.

Both envelopes on the address side are divided into similar spaces 3 for the receipt of data required, as number of coupons enclosed, when due, when deposited, where payable, so that when the one envelope is enclosed in the other, these spaces will coincide and this portion of the outer envelope is carbonized at 6 on the inside so that the data made on the outer envelope will be transferred to the face of the inner envelope.

The upper and lower portions 4, 5, of the address side of the outer envelope are also provided with spaces for other data, but these portions are not carbonized so that no transfer of this data is made on the inner envelope.

It will be the usual custom to furnish the envelopes with the one inside the other. The depositor making the deposit of coupons at his bank for collection, fills in the

2
information required, including his name and address with a pencil on the outer envelope without removing the inner envelope, then removing the inner envelope he will 5 deposit the coupons therein and return it to the outer envelope. He then makes his deposit, and the bank or collection agency removes the outer envelope and retains it for its filing record and forwards the inner 10 envelope to the place of payment.

In this way the full record for the bank is made on the outer envelope, which can be filed away either alphabetically in the name of the depositor, by date, or by some 15 filing number, while the inner envelope carries on its face all the necessary information for collection. Thus much time and labor is saved, the necessity of any coupon record book is obviated and the name of the 20 owner of the coupons or other non-essential information does not go to the payer.

Having thus described my invention, what I claim as new and desire to secure by Letters Patent, is:—

25. 1. An enclosure for interest coupons and the like, comprising duplicate envelopes to be enclosed one within the other, and means

for sealing the inner envelope with the address side of each envelope divided into lines and spaces for necessary information, 30 adapted to register with each other, and spaces on the outer envelope for additional data, with the front portion of the outer envelope provided with a zone of carbonization, whereby only the necessary information will be transferred to the inner envelope. 35

2. An enclosure for interest coupons and the like, comprising duplicate envelopes to be enclosed one within the other, with the 40 address side of each envelope divided into lines and spaces for necessary information, adapted to register with each other, and spaces on the outer envelope for additional data, with the front portion of the outer 45 envelope provided with a zone of carbonization, whereby only the necessary information will be transferred to the inner envelope, the inner envelope provided with the side flap for mailing and means for sealing same, and the outer envelope being open at the end for filing purposes. 50

AUGUST E. LINDENSCHMIDT.
